UNITED STATES PATENT OFFICE.

JOSEPH STONE, OF CHICAGO, ILLINOIS, ASSIGNOR TO STONE SAFETY POCKET COMPANY,
OF CHICAGO, ILLINOIS.

SAFETY POCKET.

Application filed April 18, 1922. Serial No. 554,637.

To all whom it may concern:

Be it known that I, JOSEPH STONE, a citizen of the United States, and a resident of Chicago, in the county of Cook and State of Illinois, have invented certain new and useful Improvements in Safety Pockets, of which the following is a specification.

My invention relates to a safety pocket located adjacent to the ordinary pocket, but having the entrance thereto so concealed that it is not obvious and cannot be readily located by pickpockets. This pocket is located between the usual pocket and the body of the garment, and its mouth is so closed 15 that articles cannot be accidentally lost.

An object of my invention is to provide such a pocket that will be highly efficient and can be combined with the ordinary pocket without any obvious modification of 20 the usual garment.

A further object of the invention is to form the welt which provides the usual facing for the ordinary pocket of such width and location that it will act as a complete 25 closure for the mouth of the secret pocket thus rendering the latter ordinarily unnoticeable.

Further objects will be apparent from the following detailed description and the appended claims.

In the drawings:

Figure 1 is a perspective view of the pocket from the outside with the ordinary flap turned up and the welt raised so as to disclose the entrance to the secret pocket.

Figure 2 is a somewhat diagrammatic view from the inside of the garment showing the various pieces that enter into the construction and the manner in which they 40 are arranged and fastened.

Figure 3 is a vertical sectional view through the structure shown in Figure 2.

Figures 4, 5, 6 and 7 are detail views showing various steps in the manufacture 45 of the pocket.

The pocket may be placed in coats, trousers, skirts or other garments, and a portion of the body of the garment is indicated at A. Two pieces 1 and 2 of equal size of the 50 garment material are superposed and stitched together as at 10 (Figure 4). These pieces are then straightened out as shown in Figure 5, laid upon the garment and one edge of the piece 1 is stitched to the garment at 9 together with a piece of tape or

other reinforcing material D. A strip 3 of cloth material of a size corresponding to that of the pocket desired is laid upon the garment and stitched thereto at 8 closely adjacent the edge of the piece 1. On the 60 under side of the garment material a piece B of lining or stiffening material is placed and the stitchings 8 and 9 pass therethrough.

A slit is then made in the garment material between the edge of the strip 1 and the 65 edge of the strip 3, this slit cutting through both the garment and the material B. The combined piece 1 and 2 is drawn through the slit, and the piece 3 is also drawn through the slit as indicated in Figure 6. 70

A piece of the garment material 4 is then taken, folded over and stitched through near the fold, an interposed piece E of tape or other reinforcing material also being fastened by this stitching 11 as shown in 75 Figure 6. The free edges of the piece 4 are then placed on the folded edge of piece 2 and fastened thereto by stitching 12, as shown in Figures 6 and 7.

A piece of pocket material 5 has its upper 80 edge folded over and stitched at 13 to the under seam of the piece 1. A second piece of pocket material 6 has its upper edge stitched to the piece 4 at its point of attachment to the piece 2. The two pieces 5 and 6 85 are sewed together around the sides and bottom as at 14, forming the secret pocket. Another piece 7 of pocket material of the desired size has its lower part turned up and stitched to the lower edge of the piece 2 at 90 15. This piece 7 overlaps the piece 3 and is stitched thereto at 16 and 17. This forms the usual pocket.

The pocket may be provided with the usual flap C and as shown in Figure 3, this flap with the folded edge of the garment material at the edge of the slit, the piece 3 and the pocket piece 7 are all held by the stitching 17. However, this flap C may be omitted as in itself it forms no part of the 95 invention.

The entrance into the ordinary pocket is indicated in Figures 2 and 3 by the arrows a, while the path into the secret pocket is indicated by the arrows b. It will be noted 105 that the stitching 10 is taken out after the parts are assembled except at the edges as clearly shown in Figure 2. The entrance to the secret pocket is therefore between the pieces 1 and 2 and up over the upper edge 110

of the piece 4. The welt formed by the piece 1 is quite broad and extends downward over the top of the piece 4 a considerable distance. Since the welt piece 1 is 5 stitched to the garment along its upper edge and to the piece 4 at its outer corners it fits smoothly over the piece 4 and completely conceals the entrance to the secret pocket. Not only is the entrance concealed, but 10 there is no indication whatever that a secret pocket exists. Even a casual examination from the inside of the garment of the members 6 and 7 does not necessarily show the existence of two pockets. Furthermore, if 15 desired, the two pockets may be made of the same size, in which case their lower and side edges might be stitched together.

The location of the secret pocket on the side of the ordinary pocket away from the 20 body of the wearer is also an important feature, since it renders it much more difficult of access. It is obvious that minor changes might be made in size, form, proportions, material, and method of assembly 25 without departing from the spirit of the invention, and in general it is to be understood that the invention is limited only by the scope of the appended claims.

I claim as my invention:

30 1. A safety pocket for garments comprising a guard welt attached to the edge of the usual pocket opening and extending downwardly, a second strip of material attached at its upper corners to the lower edge of the guard welt, these two pieces forming one side of the usual pocket and the opening between their unattached portions forming the entrance to the secret pocket, a folded strip attached to the outer side of the second strip of material and extending upwardly to near the top of the guard welt, and pieces of pocket material attached to the outside of the folded strip and the outer lower edge of the guard welt 45 and forming the secret pocket.

2. A safety pocket for garments comprising a guard welt attached to the edge of the usual pocket opening and extending downwardly, a second strip of material attached at its upper corners only to the lower edge of the guard welt, a third strip of material attached at its upper edge to the garment above the pocket opening, a piece of pocket material attached at its upper edge to the third strip and at its lower edge to the second strip, the three strips and the piece of pocket material forming the usual pocket, and the opening between the unattached edges of the guard welt and the second strip forming the entrance to the secret pocket, a folded strip attached to the outer edge of the second strip and extending upwardly to near the top of the

guard welt, and pieces of pocket material attached to the outside of the folded strip 65 and the outer lower edge of the guard welt and forming the secret pocket.

3. A safety pocket for garments comprising a pocket having the usual opening, a second pocket located between the ordinary 70 pocket and the garment, and a guard welt attached to the garment at the usual pocket opening and stitched down at its sides so that it conceals and protects the entrance to the second or safety pocket.

4. A safety pocket for garments comprising a pocket having the usual opening, a second pocket located between the ordinary 75 pocket and the garment, a folded strip forming the upper edge of the second pocket, a guard welt attached to the garment at the usual pocket opening and stitched down at its sides, said welt extending downward over the folded strip and thus protecting the entrance to the second or safety pocket.

5. A safety pocket for garments comprising a pocket having the usual opening, a second pocket located between the ordinary 80 pocket and the garment and having a folded strip forming its upper edge, a guard welt attached to the garment at the usual pocket opening and extending downward over the folded strip, and a piece of pocket material 85 passing up over the folded strip and downwardly and being attached to the lower edge of the guard welt, whereby the entrance to the second or safety pocket is concealed and protected.

6. A safety pocket for garments comprising a pocket having the usual opening, a second pocket located between the ordinary 90 pocket and the garment and having a folded strip forming its upper edge, a guard welt attached to the garment at the usual pocket opening and extending over the folded strip, a piece of pocket material attached to the lower edge of the folded strip, and a second 95 piece of pocket material passing up over the folded strip and downwardly and being attached to the lower edge of the guard welt, whereby the entrance to the second or safety pocket is concealed and protected.

7. A safety pocket for garments comprising a pocket having the usual opening, a second pocket located between the ordinary 100 pocket and the garment, and a guard welt attached to the garment at the usual pocket opening and extending over the folded strip, a piece of pocket material attached to the lower edge of the folded strip, and a second 105 piece of pocket material passing up over the folded strip and downwardly and being attached to the lower edge of the guard welt, whereby the entrance to the second or safety pocket is concealed and protected.

In testimony whereof, I have hereunto 110 subscribed my name.

JOSEPH STONE.
